OTHER PUBLICATIONS

U.S. Appl. No. 29/494,441, titled "Display Screen With Animated User Interface," in the names of Robertus Mariet and Patrick Hofmann filed on Jun. 20, 2014.

(Continued)

Primary Examiner — Kevin Rudzinski(74) *Attorney, Agent, or Firm* — Finnegan, Henderson, Farabow, Garrett & Dunner LLP(57) **CLAIM**

The ornamental design for a display screen with graphical user interface, as shown and described.

DESCRIPTION

The single FIGURE is a front view of a display screen with graphical user interface showing the new design.

The broken lines of uneven length show the display screen and form no part of the claimed design. The broken lines of even length shown in the drawings illustrate portions of the display screen with graphical user interface that form no part of the claimed design.
